CLAIM

The ornamental design for an image pickup apparatus, as shown and described.

DESCRIPTION

FIG. 1 is a front elevational view of an image pickup apparatus showing our new design;
FIG. 2 is a rear elevational view thereof;
FIG. 3 is a top plan view thereof;
FIG. 4 is a bottom plan view thereof;
FIG. 5 is a left side elevational view thereof;
FIG. 6 is a right side elevational view thereof; and,
FIG. 7 is a perspective view taken from the front, top and right side of the image pickup apparatus.
